D. ATWATER

UNION SUIT

Filed June 7, 1922

FIG. 1.

FIG. 2.

FIG. 3.

FIG. 4.

David Atwater.

INVENTOR.

BY

Frank A. Cutten,

ATTORNEY.

UNITED STATES PATENT OFFICE.

DAVID ATWATER, OF WESTFIELD, MASSACHUSETTS.

UNION SUIT.

Application filed June 7, 1922. Serial No. 566,566.

To all whom it may concern:

Be it known that I, DAVID ATWATER, a citizen of the United States of America, and a resident of Westfield, in the county of 5 Hampden and State of Massachusetts, have invented a new and useful Union Suit, of which the following is a specification.

My invention relates to improvements in union suits, and more particularly to improvements in union suits such as those which form the subject of my application for Letters Patent of the United States, filed in the United States Patent Office April 25, 1922, and serially numbered 556,492, and references 10 sides in a union suit provided with permanently affixed supporting inserts, panels, tabs, or equivalent members, the portions of the garment to which such supporting members are attached usually being reenforced by stitching or otherwise, and hose supporters of any suitable type connected with or attachable to and detachable from said supporting members, all as hereinafter set forth.

25 The union suits employed in this as in the other case are usually of the full-length variety in contradistinction to the knee-length variety, it being sufficient, however, for the legs of the same to extend even only 30 a short distance below the knees of the wearer, and as a rule such suits are of the knitted or woven type which have seams on the insides of the leg portions thereof. The aforesaid supporting members or tabs are 35 attached to the aforesaid seams or to the seamed parts of the legs of the union suit, most generally below those portions of said legs that cover the knees of the wearer.

40 The hose supporters may be made up in a number of different ways and out of a number of different materials, but more frequently will consist of either elastic or non-elastic tapes to which are attached buttons or their equivalents and clasps or their equivalents.

45 The primary object of my invention is to produce a combination union suit and hose supporters, to the end that the separate and individual or independent hose supporters commonly used shall be dispensed with. It is difficult properly to adjust the ordinary hose supporter to the leg so that it will not bind on the one hand or be too loose on the other. With the present invention provision is made for supporting the hose without binding the leg or producing any discom-

fort whatever. In this case the hose are supported or held up in place properly and securely, and the strain is distributed throughout the legs and the other portions of the garment in such a manner as to be unappreciable. Furthermore, the hose-supporting means practically eliminate two separate articles of wearing apparel, and consequently excel in convenience and as time-savers. Being attached to the seams or seamed parts of the union suit the hose-supporting means are not liable to tear or unduly strain the fabric of such suit.

50 A further object is to provide a union suit with hose-supporting means which are comparatively simple and inexpensive, and which do not impair in any way the usefulness or ordinary utility of such suit, or interfere with laundering the same.

55 The hose supporters themselves, which form parts of this invention, are readily attachable to and detachable from the tabs provided therefor, they can be easily and quickly adjusted in length whenever necessary, and can be attached to and detached from the hose with as much facility as any other hose supporters.

60 Other objects and advantages will appear in the course of the following description.

I attain the objects and secure the advantages of my invention by the means illustrated in the accompanying drawings, in which—

65 Figure 1 is a perspective view of a union suit which embodies a practical form of my invention; Fig. 2, an enlarged front elevation of a portion of one of the legs of said suit, with one of the supporting tabs attached thereto; Fig. 3, a vertical section 70 taken on lines 3—3, looking in the direction of the associated arrow, in Fig. 2, and, Fig. 4, an enlarged detail of one of the hose supporters.

75 Similar reference characters designate 80 similar parts throughout the several views.

An ordinary knitted or woven union suit is represented at 1 in Fig. 1, which suit has full-length leg portions 2—2, seamed at 4 on the inside from the bottoms thereof to the 85 crotch. Attached to and extending across the seams 4, below the parts of the legs 2 that cover the knees of the wearer, is a pair of supporting tabs 5, one of such tabs being attached to one of such legs.

90 Each tab 5 preferably consists of a triangular piece of strong and firm fabric, and

the same is applied to one of the legs 2 of the garment over or across an intermediate portion of the seam 4 in such leg, on the outside of the fabric of said garment, with 5 the base of such tab at the bottom. The sides of the tab 5 are stitched or otherwise fastened to the leg 2, as at 6—6. There is a slot 7 in the tab 5, which slot is parallel with the base or bottom edge thereof. Preferably 10 there are oblique lines of stitching 8—8 extending downwardly from the lower corners of the tab 5 to the seam 4 below said tab.

Each of the hose supporters herein shown and described consists of a tape 9 which is 15 provided at one end with a clasp 10, and has adjustably connected therewith at or adjacent to the other end a buckle 11 having thereon a button 12. Both the clasp 10 and the buckle 11 are of the usual and well-known types and function conjunctively in 20 the usual manner.

The widths of the clasp 10 and the tape 9, of each hose supporter, are such as to enable said clasp to be passed through the slot 25 7 in either of the tabs 5, from the inside, and to be drawn downwardly on the outside, it being understood that the bottom edges of the tabs are free, and that said tabs are unattached, except at the side edges, to the 30 legs 2.

When the clasp 10, of each hose supporter, is passed in the manner previously described through the slot 7 in the tab 5 from which said supporter is to be suspended, said clasp 35 is moved downwardly and draws with it through said slot a portion of the tape 9, with which said clasp is connected, until the clasp and its associated buckle 11 are approximately at the same elevation, the 40 former being in front and the latter behind.

The length of either hose supporter can be increased or decreased by making the necessary adjustment of the buckle 11 on the tape 9 of said supporter. The parts are so adjusted as to locate the buttons 12 at such 45 distances below the tabs 5 as to enable the clasps 10 readily to engage said buttons and a hose caught over the same.

In practice, while either clasp 10 is disengaged from its associated button 12, the upper portion of a hose is caught over said button, the wide portion of the clasp 10 is closed over the hose and button and said clasp is pulled upwardly until said button 50 with its covering of hose is crowded or forced into the narrow portion of the clasp, the tape 9 to which are attached said clasp and the buckle 11 carrying said button meanwhile automatically adjusting itself in the tab 5 which supports the same. The hose 55 is now held securely by the supporting elements and prevented from working downwardly on the leg. The strain of the hose is transmitted from the engaging button and 60 clasp to the seamed portions of the garment

leg with which the supporting tab 5 is connected, and distributed to other portions of said leg, and even to the garment above the same. A fragment 13 of a hose is represented as being in the grasp of the hose supporter shown in full lines in Fig. 1. 70

In releasing the hose from either supporter, the clasp and buckle involved are manipulated in such a manner as to disengage the clasp from the hose-covered button, after which the hose is removed from said button. 75

Ordinarily the hose supporters are removed from the tabs 5 when the union suit is to be laundered, and afterwards said supporters are returned to place and suspended from said tabs. This is an important feature, because the garment may thus be freed from the metal parts of the hose-supporting means before said garment is laundered, and 80 the hose supporters are not subjected to the action thereon of soap and water, which would be detrimental thereto, especially when the tapes 9 are made of elastic material. The tabs 5 do not, of course, interfere 85 in any way with the washing of the garment, nor with the use of the garment without supporting means for the hose suspended from said tabs, provided such use be desired. 90

It is to be understood, as hereinbefore 95 stated or intimated, that other forms or types of hose supporters may be employed, provided the same be capable of attachment to the tabs 5, hence I do not intend to be limited to the particular type of the same 100 herein shown and described; and in this connection it is desired to state that more or less change in the shape, size, and formation of the tabs and the parts of the legs of the garment to which said tabs are applied 105 may be made, without departing from the spirit of my invention, or exceeding the scope of what is claimed.

What I claim as my invention, and desire 110 to secure by Letters Patent, is—

1. As an improved article of manufacture. A bifurcated union suit having seams on the insides of the legs thereof, and each leg provided with a supporting member for a pendant hose supporter, said member secured 115 over and to the seam by stitching.

2. The combination, in a bifurcated union suit, with a supporting member for each leg, said member stitched at its side edge portions to a leg of the suit, the bottom edge of said member being free, and there being a slot in said member adjacent to said bottom edge, of a tape receivable in said slot, and provided with a clasp and button-provided buckle. 120
